DESIGN FOR A TABLE OR SIMILAR ARTICLE

David Raucher, Brooklyn, N. Y.

Application September 23, 1944, Serial No. 115,433.

Term of patent 3½ years

(Cl. D33—14)

To all whom it may concern:

Be it known that I, David Raucher, a citizen of the United States and residing at Brooklyn, in the county of Kings and State of New York, have invented a new, original, and ornamental Design for a Table or Similar Article, of which the following is a specification, reference being had to the accompanying drawing, forming a part thereof.

Fig. 1 is a perspective view of a table or similar article, showing my new design.

Fig. 2 is an end view thereof.

I claim:

The ornamental design for a table or similar article, substantially as shown.

DAVID RAUCHER.
